United States Patent Office.

ALFRED RIX, OF SAN FRANCISCO, CALIFORNIA.

Letters Patent No. 82,440, dated September 22, 1868.

IMPROVEMENT IN FASTENINGS FOR BUTTONS.

The Schedule referred to in these Letters Patent and making part of the same.

TO ALL WHOM IT MAY CONCERN.

Be it known that I, ALFRED RIX, of the city and county of San Francisco, and State of California, have invented a new and improved Mode of Fastening Buttons to Garments; and I do hereby declare that the following is a full and exact description thereof, reference being had to the accompanying drawings, forming a part of this specification, in which—

Figure 1 is a central section view of a button attached to the cloth with my fastener, the section being transverse as to the button and washer, and longitudinal as to the shank.

Figures 2, 5, and 6 are similar views of varied modes of attaching the shank to the body of the button.

Figure 3 is a top view of the washer closed, and

Figure 4 is a top view of the washer open.

Similar letters of reference in the different figures indicate the same parts.

The nature of my invention consists in forming the common rivet and washer-fastening by bending or springing the washer over or behind the rivet-head ready made, instead of first passing the rivet through the washer, and then heading it in the usual way.

The shank, made of some strong metal, with a head small and rounded, so as to pass easily through the fabric without injuring it, constitutes the chief and constant element of my device, whilst the washer may be varied, both in style and application, indefinitely.

To enable others skilled in the art to which my invention belongs, or to which it most nearly appertains, to make and use the same, I will proceed to describe it particularly with reference to the drawings.

The shank consists of the body *a*, the neck *b*, and head *c*.

The body *a*, upon which the button-hole bears, should not be too large for the hole, and yet large enough to allow a shoulder at its junction, with the neck sufficient to prevent the body from slipping through the neck-hole.

The body of the shank may be secured to the body of the button in any proper manner, either rigidly or by a joint.

Fig. 2 shows a ball-and-socket attachment; fig. 5 shows a hook-eye or staple attachment; fig. 6 shows a plain shank, with a shoulder formed by a loose ferrule of rubber or metal.

In many cases, and especially in buttons designed for ornament, the shoulder can be dispensed with altogether, and the button allowed to rest directly against the garment.

The button is held to the garment by the washer, figs. 3 and 4, which fits closely about the neck, and into which the head may be countersunk or not, thus forming a fastening equivalent to a rivet and washer.

The washer is prepared for application by being divided on one side, and left open far enough to go over the head or across the neck of the shank, as shown in fig. 4.

The button is fastened to the garment *e* by passing the head of the shank through a hole made in the garment with a bodkin, and then putting the washer over the head, or across the neck, and closing it by nippers applied to its sides at *x* and *y*.

A slight indenture in the face of the jaws of the nippers, at the points of contact with the washer, will facilitate the operation.

In case the shank is jointed to the button so as to swing loosely, it can be held by the nippers applied to its exterior end to aid in passing it through the garment.

As the nippers cause the bending to take place entirely at the point opposite to the opening at *z*, in order to make a good fit and neat appearance, the washer must be formed accordingly, that is, oblong, as shown in fig. 4.

Having thus described my invention, what I claim as new, and desire to secure by Letters Patent, is—

The headed shank and open washer for securing the button to the cloth or garment, constructed substantially in the manner and for the purpose set forth.

ALFRED RIX.
